(57) **CLAIM**

The ornamental design for a lap desk with slot and mouse pad, as shown and described.

DESCRIPTION

FIG. 1 is a right elevated perspective of a particular embodiment of the present invention.

FIG. 2 is a section view as indicated in FIG. 3 of the slot in the particular embodiment of the present invention shown in FIG. 1.

FIG. 3 is a top plan view of the particular embodiment of the present invention shown in FIG. 1.

FIG. 4 is a bottom plan view of the particular embodiment of the present invention shown in FIG. 1.

FIG. 5 is a left side elevational view of the particular embodiment of the present invention shown in FIG. 1, the right side elevational view thereof being the mirror image of FIG. 5.

FIG. 6 is a rear elevational view of the particular embodiment of the present invention shown in FIG. 1.

FIG. 7 is a front elevational view of the particular embodiment of the present invention shown in FIG. 1.

FIG. 8 is a right elevated perspective of another particular embodiment of the present invention.

FIG. 9 is a section view as indicated in FIG. 10 of the slot in the particular embodiment of the present invention shown in FIG. 8.

FIG. 10 is a top plan view of the particular embodiment of the present invention shown in FIG. 8.

FIG. 11 is a bottom plan view of the particular embodiment of the present invention shown in FIG. 8.

FIG. 12 is a left side elevational view of the particular embodiment of the present invention shown in FIG. 8, the right side elevational view thereof being the mirror image of FIG. 12.

FIG. 13 is a rear elevational view of the particular embodiment of the present invention shown in FIG. 8; and,

FIG. 14 is a front elevational view of the particular embodiment of the present invention shown in FIG. 8.
